(57) **CLAIM**

The ornamental design for a generator housing, as shown and described.

DESCRIPTION

FIG. 1 is a top perspective view of a generator housing illustrating our new design;

FIG. 2 is a bottom perspective view thereof;

FIG. 3 is a top view thereof;

FIG. 4 is a bottom view thereof;

FIG. 5 is a side view thereof, the opposite side view being a mirror image thereof;

FIG. 6 is another side view thereof;

FIG. 7 is another side view thereof; and,

FIG. 8 is a cross section view thereof, taken along line 8-8 as shown in FIG. 3.

The dashed broken lines in the drawings illustrate portions of the generator housing that form no part of the claimed design.

The dot-dash broken lines in the drawings define the boundaries of the claimed design and form no part thereof.

The ornamental design is not limited in the scale or dimension as shown herein. Applicant specifically disclaims any broken lines as features of the claimed invention or embodiment as appropriate.
